Filed June 1, 1967, Ser. No. 7,333

Term of patent 14 years

(Cl. D86—8)

FIG. 1 is a side elevational view of a hair styling tool showing my new design, the opposite side having an appearance similar to that shown;

FIG. 2 is a bottom plan view;

FIG. 3 is a top plan view;

FIG. 4 is an end elevational view looking from left to right at FIG. 1;

FIG. 5 is an end elevational view looking from right to left at FIG. 1;

FIGS. 6 and 7 are sectional views taken on the planes of lines 6—6 and 7—7, respectively, of FIG. 1;

FIG. 8 is a fragmentary side elevational view similar to the left hand portion of FIG. 1 and showing an alternate tine arrangement of the tool; and

FIG. 9 is a fragmentary side elevational view similar to FIG. 8 showing another alternate tine arrangement.

The dominant feature of the design resides in those portions shown in solid lines, the dotted lines showing identifying conventional comb teeth.

The characteristic feature resides in the combination in which the handle portion between the longitudinal prongs and the comb is recessed and has a marginal border and includes at one side, within the general area of the tool width, an indentation extending angularly from the end of the tool and terminating in a curved end intermediate of the handle, as shown.

I claim:

The ornamental design for a hair styling tool, as shown and described.
